CLAIM

The ornamental design for a rear wheel drive assembly for a scooter, as shown and described.

DESCRIPTION

FIG. 1 is a side view in elevation of a first side of a rear wheel drive assembly for a scooter showing my new design;

FIG. 2 is a side view in elevation of a second side of the drive assembly which is opposite to the first side;

FIG. 3 is a top plan view of the drive assembly;

FIG. 4 is a bottom plan view of the drive assembly;

FIG. 5 is a rear view in elevation of the drive assembly;

FIG. 6 is a front view in elevation of the drive assembly;

FIG. 7 is a perspective view of the drive assembly in an assembled configuration; and,

FIG. 8 is a perspective view of the drive assembly in an exploded configuration.
